ROTARY MACHINE

William D. Davidson, Los Angeles, Calif., assignor to Emsco Derrick & Equipment Company, Los Angeles, Calif., a corporation of California

Application October 8, 1938, Serial No. 233,967

16 Claims. (Cl. 255—23)

My invention relates to improvements in rotary machines of the class commonly employed in the drilling of oil wells and resembles in purpose my invention for Rotary machine and bushing therefor disclosed in my copending application, Serial No. 228,585, filed September 6, 1938.

In order that the features and advantages of my invention may be better understood, brief reference will be made to the present practice of drilling oil wells by the rotary method.

It is common practice to employ a drill pipe which extends into the hole being drilled and which has a bit secured to the lower end thereof. The upper end of the drill pipe is provided with a drive stem or kelly which is usually of rectangular cross-section, which kelly extends through the table of the rotary machine which is supported on the derrick floor. For the purpose of rotatably driving the kelly it is the present practice to provide a drive bushing or kelly bushing which is placed in the opening of the table of the rotary machine, which drive bushing has an opening of cross-sectional shape corresponding to that of the kelly and through which the kelly extends. When stands of drill pipe are being connected or disconnected from the string of drill pipe slips are employed which are supported in the table by a table bushing or master bushing, these slips fitting into a tapered opening of the table bushing and being caused to tightly grip the pipe so as to support the same.

In the conventional rotary table the drive bushing is supported by the table bushing and the twisting of the kelly tends to spread the table bushing causing wear thereon and on the inside of the rotary table. This wear results in an improper supporting of the table bushing and resultant poor fit between the slips and the tapered opening of the table bushing, and therefore there is an imperfect contact between the slips and the drill pipe.

It is an object of my invention to provide a rotary machine of the general character referred to above in which wear on the table bushing, or master bushing, by reason of engagement of the drive bushing therewith is wholly eliminated.

It is also an object of my invention to provide a rotary machine in which the drive bushing and table bushing are independently driven by the table and in which these two bushings are wholly out of contact with each other so that the drive bushing will not transmit any driving forces or weight to the table bushing.

It is a still further object of my invention to provide a rotary machine of the character pointed

out in the preceding paragraph in which the drive bushing is substantially flush with the top wall of the table.

It is a still further object of my invention to provide as a new article of manufacture a table for use as an element of a rotary machine, which table has a table opening which provides an upper shouldered section, a lower shouldered section, and a depending skirt section, and in which each of the shouldered sections has an upright driving shoulder and a lateral supporting shoulder in different horizontal planes and is vertically staggered or offset so as to be helically arranged.

It is a still further object of my invention to provide a rotary machine having the features and advantages pointed out in one or more of the preceding paragraphs and in which the diameter of the table may be held to a minimum.

It is a still further object of my invention to provide a rotary machine of the character pointed out in one or more of the preceding paragraphs in which the two shouldered sections are substantially the same diameter.

It is a still further object of my invention to provide a rotary machine of the character pointed out in one or more of the preceding paragraphs in which the upper and lower shoulders are helically arranged or are circumferentially offset or staggered.

Other objects and advantages of my invention will be pointed out in the course of the following detailed description of alternative forms of my invention which have been chosen for the purpose of instructing those skilled in the art as to how my invention may be practiced. It should be understood, however, that my invention is not limited to the details of construction to be hereinafter described and illustrated in the accompanying drawings, but my invention should be construed to cover all modifications thereof which come within the spirit and scope of the preceding statement of invention and appended claims.

Referring to the accompanying drawings:

Fig. 1 is an elevational view partly in section showing a preferred form of my invention.

Fig. 2 is a plan view of the table end of the rotary machine shown in Fig. 1.

Fig. 3 is a fragmentary section taken on the line 3—3 of Fig. 1.

Fig. 4 is a fragmentary vertical section taken on the line 4—4 of Fig. 2.

Fig. 5 is a perspective view of the rotary table, master bushing, and drive bushing in separated relationship so that the shape of the parts and

arrangement of the shouldered sections and shoulders thereof may be clearly illustrated.

Fig. 6 is a fragmentary sectional view taken on the line 6—6 of Fig. 2 showing the lock means for locking the drive bushing.

Fig. 7 is a fragmentary view taken on the line 7—7 of Fig. 6.

Fig. 8 is a fragmentary sectional view taken on the line 8—8 of Fig. 2 showing the lock means for the table bushing of my invention.

Fig. 9 is an elevational sectional view of the table end of the rotary machine and shows the position of the parts with the pipe supporting slips in use.

Fig. 10 is a fragmentary sectional view illustrating an alternative form of my invention.

Referring to Figs. 1 to 9 inclusive of the drawings, I will now describe the form of my invention illustrated in these views. The numeral 11 represents a base on which a rotary table 12 is rotatably supported by a main bearing 14. The table 12 supports a ring gear 15 which is engaged by a pinion 16, which pinion 16 is supported on a shaft 17 which may be rotated through the medium of a sprocket 18.

The table 12 has a top portion 29 which provides a top wall 21. Depending from the top portion 28 is a skirt 22 which is of general cylindrical shape and is surrounded by the main bearing 14, and its lower end may support a suitable hold-down bearing means 23 of any of the general forms now employed in the art.

The general construction of the rotary machine does not constitute the essence of the present invention, and my invention which will now be described may be incorporated in any of the rotary machines now in common use in the industry.

The table 12 has a table opening 24 which is concentric to the axis of rotation of the table and is divided into three sections, an upper shouldered section 26, a lower shouldered section 27, and a cylindrical or skirt section 28. The upper shouldered section 26 is preferably of polygonal cross-section and has vertical walls 29 which constitute driving shoulders and has lateral or horizontal walls 30 which constitute supporting shoulders. These walls cooperate to define a number of upper pockets 30a which are symmetrically arranged on equi-spaced lines radiating from the axis of rotation of the table. The lower shouldered section 27 is likewise of polygonal cross-section and has vertical walls 33 which constitute driving shoulders and lateral or horizontal walls 34 which constitute supporting shoulders. These walls cooperate to define a number of lower pockets 34a which are symmetrically arranged on equi-spaced radial lines. The upper and lower shouldered sections 26 and 27 are preferably, although not necessarily, of the same cross-sectional size or diameter and the skirt section 28 is preferably of smaller cross-sectional size than the two shouldered sections. It will be noted that the upper and lower pockets 30a and 34a are alternately placed on a circle. It will also be noted that the supporting shoulders 30 and 34 are arranged in a circle in different horizontal and vertical planes and are therefore helically positioned. It will further be noted that the shoulders 33 extend to the top wall 21 of the table so that the lower shouldered section is accessible from the top of the rotary table so that the table bushing may be readily dropped or lowered into place. It will further be seen that the shoulders 29 and 33 are circumferentially

staggered and that the lower portions of the shoulders 33 are in a different horizontal plane than the shoulders 29 and that, therefore, the lower portions of the shoulders 33 and the shoulders 29 are helically arranged.

In Fig. 9 I have illustrated a bushing 37 in place in the table opening 24, this bushing 37 constituting the bushing commonly referred to as the table bushing, slip supporting bushing, or master bushing. This table bushing 37 is preferably split into two halves 38 so that it may be installed in the table opening while a drill pipe, such as 40, is extending through the table opening. The table bushing 37 has an upper shouldered portion 41 and a lower cylindrical portion 42. The shouldered portion 41 rests in the lower shouldered section 27 of the opening 24 and has upright driving shoulders 43 which engage the lower parts of the driving shoulders 33 of the rotary table whereby relative rotation between the table and the table bushing is prevented and whereby the table may be caused to drive the table bushing. The shouldered portion 41 also has lateral supporting shoulders 44 adapted to engage the supporting shoulders 34 of the lower shouldered section 27 in order that the table bushing may be supported. The corners of the shouldered portion 41 constitute projections 44a which rest in the lower pockets 34a. The cylindrical portion 42 of the table bushing 37 has a cylindrical wall 46 which may engage a wall of the skirt section 28. The table bushing provides an inner wall 47 which is conical or tapered, as illustrated, and receives a plurality of pipe supporting slips 48 which, as illustrated in Fig. 3, engage and support the drill pipe 40. There are preferably three slips which are inserted into the table opening from the top thereof by workmen on the derrick floor and which may be provided with suitable handles (not shown).

The table bushing 37 is supported in the lower shouldered section and skirt section with the conical or tapered seat provided by the wall 47 in a position concentric to the axis of the table opening 24. The table bushing holds the slips 48 in proper aligned position to properly engage and support the drill pipe 40.

In Figs. 1 to 4 and 6 to 8 I have illustrated my invention with a drive bushing 50 thereof in place and with the parts in the positions they occupy when the kelly is being driven. The kelly bushing or drive bushing of my invention is preferably formed in two parts 51 and 52 which coengage along a diametral line 53. The drive bushing 50 has a central opening 54 which is of rectangular or other polygonal cross-section and is adapted to drivably engage a drive stem or kelly 55 which is usually of rectangular cross-section. The drive bushing 50 includes a shouldered portion 56 which has vertical walls 59 which constitute driving shoulders and are adapted to engage the driving shoulders 29 of the upper shouldered section 26, and they may also, if desired, engage the upper portions of the shoulders 33 so that a maximum area of driving engagement may be obtained. The shouldered portion 56 also has a lower wall 63 which constitutes supporting shoulders which are adapted to engage the supporting shoulders 34 of the upper shouldered section 26 of the opening 24. The shouldered portion 56 has corners or points which constitute projections 60a which rest in the upper and lower pockets 30a and 34a. The depending skirt of the drive bushing 50 projects downwardly into the conical opening pro-

vided by the table bushing 37 and is provided in order that the walls of the opening 54 may be relatively long to give ample driving engagement between the drive bushing and kelly. When 5 in driving position, as shown in the figures referred to above, the drive bushing 50 is supported wholly within the table opening 24 and with its top wall flush with the top wall 21 of the table. In this position the drive bushing is 10 supported by the supporting shoulders 38 and may be driven by the driving shoulders 29 or the upper portions of the driving shoulders 33 or both. During this operation the slips 48 are not in use and are removed in order that 15 the lower part of the drive bushing may be extended into the tapered opening of the table bushing.

As clearly illustrated in Figs. 1 and 4, there is 20 no weight transmitting contact whatsoever between the drive bushing 50 and the table bushing 38, these parts being preferably separated by a small space 62. The table therefore independently supports the drive bushing and the table bushing and independently drives each of these 25 bushings. No driving force or weight is transmitted from the drive bushing 50 to the table bushing 37.

In order that the bushings may be locked in the 30 table I provide suitable lock means. The drive bushing 50 is locked in place by a lock means which includes a latch member 65 mounted on a rotatable shaft 66 which extends upwardly to the 35 top wall 21 of the table and which, upon rotation, is movable from a position within a pocket 67 of the table, which position is illustrated by dotted lines 67a, into a locking position which is shown by full lines in Figs. 6 and 7, and in which position the end of the latch 65 extends into a recess 68 of the drive bushing 50. The table bushing 37 is locked in place by a similar construction, as 40 illustrated in Fig. 8, which includes a latch member 70 movable between latched and unlatched positions by a rotatable shaft 71 on which the latch member is mounted, and which is adapted to extend into a recess 72 of the table bushing 37 when in latched position. By inserting a suitable wrench into polygonal openings 73 formed in the upper ends of the rods 66 and 71 the latches 45 65 and 70 may be operated in order to lock or unlock the bushings with respect to the table.

In Fig. 10 I illustrate another form of drive bushing identified by the numeral 90, which type of bushing is intended to be supported at all times by the kelly 55. This type of drive bushing includes a one-piece body which has a cylindrical wall 91 which extends upwardly from the shouldered portion 59 thereof and which cooperates with the remainder of the bushings to provide a central opening 92 in which kelly engaging means 55 or blocks 93 are supported, these blocks being retained between lower shoulders 94 and an upper retaining member 95 which is bolted to the upper end of the wall 91. When the kelly is moved upwardly the joint 97 at the lower end thereof will engage the drive bushing and lift it upwardly from the table opening. In this form of my invention it is not necessary to manually remove the drive bushing from place as in the other form of my invention.

70 In the use of either of the forms of my invention disclosed herein both the table and drive bushings are in place during the time that the kelly is being driven. The table bushing remains in place at all times ready for use but is used only 75 when the slips 48 are in use. The table bushing

of my invention is not called upon to support or drive the drive bushing and no supporting or driving forces are transmitted from the drive bushing through the table bushing to the table. The table bushing and walls or shoulders engaging the same are not subjected to wear which would result if the table bushing supported or drove the drive bushing, and therefore these interengaging shoulders or surfaces will remain in good condition and alignment over a long period of time 10 and will support the slips 48 in a concentric and aligned position over long periods of use. If it is necessary to remove large objects through the rotary table the entire table opening may be made accessible by first unlocking the table bushing and then removing it from the table opening.

The design of the table is an important part of my invention because it enables the features and advantages thereof to be accomplished by the use of shouldered sections of substantially the same 20 diameter. This is important because it is not necessary in the practice of my invention to enlarge the diameter of the table which would result in greater centrifugal forces being set up in the 25 table due to its greater diameter.

I understand that various modifications and alterations may be made in my invention without departing from the spirit and scope thereof, and I therefore wish my invention to be broadly construed in accordance with the statement of 30 invention and appended claims.

I claim as my invention:

1. In a rotary machine of the class described, the combination of: a base; a table rotatably supported by said base, said table having a table opening which includes an upper shouldered section and a lower shouldered section, each of said sections including a driving shoulder and a supporting shoulder, the supporting shoulders of said sections being circumferentially arranged with 40 said supporting shoulders of said upper section alternately arranged between said supporting shoulders of said lower section; a table bushing in said opening having a shouldered portion positioned in said lower shouldered section of said 45 table opening, said shouldered portion having a driving shoulder and a supporting shoulder engageable with corresponding shoulders of said lower shouldered section; and a drive bushing, positioned in said table opening, having a shouldered portion in said upper shouldered section, said shouldered portion having a driving shoulder and a supporting shoulder engageable with corresponding shoulders of said upper shouldered section, said table bushing and said drive bushing 50 being independently supported by said table and said drive bushing transmitting no driving forces or weight to said table bushing.

2. In a rotary machine of the class described, the combination of: a base; a table rotatably supported by said base, said table having a table opening having a plurality of upper pockets circularly arranged at the upper end of said table opening and a plurality of lower pockets circumferentially arranged at the upper end of said table 60 opening, said lower pockets being located between said upper pockets; a table bushing in said table opening having a shouldered portion resting in said lower pockets; and a drive bushing in said table opening having a shouldered portion resting in said upper pockets.

3. As a new article of manufacture, a table for use as an element of a rotary machine of the class described, said table having a top portion, a skirt depending therefrom, and a table opening through 75

said top portion and skirt, said table opening having an upper shouldered section, a lower shouldered section, and a skirt section therebelow, said upper and lower shouldered sections each having 5 a driving shoulder and a supporting shoulder, and said lower shouldered section being of substantially the same cross-sectional size as said upper shouldered section.

4. As a new article of manufacture, a table for 10 use as an element of a rotary machine of the class described, said table having a top portion, a skirt depending therefrom, and a table opening through said top portion and skirt, said table opening having circumferentially staggered upper 15 and lower pockets at the upper end thereof and accessible from the top of said table, said pockets respectively having upper and lower supporting shouiders.

5. As a new article of manufacture, a table 20 for use as an element of a rotary machine of the class described, said table having a top portion, a skirt depending therefrom, and a table opening through said top portion and skirt, said table opening having circumferentially staggered 25 upper and lower pockets of substantially identical cross-sectional shape at the upper end thereof and accessible from the top of said table, said pockets respectively having upper and lower supporting shouiders.

6. As a new article of manufacture, a table 30 for use as an element of a rotary machine of the class described, said table having a top portion, a skirt depending therefrom, and a table opening through said top portion and skirt, 35 said table opening having circumferentially staggered and alternately arranged upper and lower pockets at the upper end thereof and accessible from the top of said table, said pockets respectively having upper and lower supporting shouiders.

7. In a rotary machine of the class described, 40 the combination of: a base; a table rotatably supported by said base, said table having a table opening which includes an upper shouldered section and a lower shouldered section, each of said sections including a driving shoulder and a supporting shoulder, said upper and lower sections being circumferentially arranged around the upper part of said table opening and in direct connection therewith with said supporting and driving shoulders of said upper section being alternately arranged between said driving and supporting shoulders of said lower section; a table bushing in said opening having a shouldered portion positioned in said lower shouldered section of said table opening, said shouldered portion having a driving shoulder and a supporting shoulder engageable with corresponding shoulders of said lower shouldered section; 50 and a drive bushing, positioned in said table opening, having a shouldered portion in said upper shouldered section, said shouldered portion having a driving shoulder and a supporting shoulder engageable with corresponding shoulders of said upper shouldered section, said table bushing and said drive bushing being independently supported by said table and said drive bushing transmitting no driving forces or weight to said table bushing.

8. In a rotary machine of the class described, 60 the combination of: a base; a table rotatably supported by said base, said table having a table opening provided with a plurality of spaced upper supporting shoulders surrounding and connected to said table opening and a plurality of

lower supporting shoulders surrounding and connected to said table opening, said upper and lower supporting shoulders being arranged in the same annular area which surrounds said table opening so that in plan said lower supporting shoulders are positioned between said upper supporting shoulders, and having upper and lower driving shoulders arranged in said annular area: a table bushing in said table opening having a shouldered portion having supporting shoulders engaging said lower supporting shoulders of said table and having driving shoulders engaging at least a part of said driving shoulders of said table; and a drive bushing in said table opening having a shouldered portion which has supporting shoulders engaging said upper supporting shoulders of said table and driving shoulders engaging at least a part of said driving shoulders of said table.

9. In a rotary machine of the class described, 20 the combination of: a base; a table rotatably supported by said base, said table having a table opening having upper and lower pockets, said upper and lower pockets being alternately arranged in an annular area which surrounds said table opening and said pockets connecting directly to said table opening; a table bushing in said table opening having a shouldered portion resting in said lower pockets; and a drive bushing in said table opening having a shouldered portion resting in said upper pockets.

10. As a new article of manufacture, a table 30 for use as an element of a rotary machine of the class described, said table having a top portion, a skirt depending therefrom, and a table opening 35 through said top portion and said skirt, said table opening having upper and lower pockets which are of substantially identical cross-sectional shape at the upper end thereof and accessible from the top of said table, said pockets respectively having upper and lower supporting shouiders and said pockets being alternately arranged in an annular area which surrounds the upper end of said table opening, and said pockets being directly connected to said table opening.

11. In a rotary machine of the class described, 45 the combination of: a base; a table rotatably supported by said base, said table having a top portion, a skirt depending therefrom, and a table opening through said top portion and skirt, said table opening having circumferentially staggered and alternately arranged upper and lower pockets of substantially the same diameter at the upper end thereof and accessible from the top of said table, said pockets respectively providing 50 upper and lower supporting shoulders and driving shoulders extending from the supporting shoulders to the top surface of said table; a table bushing in said opening having shouldered portions equal in number to and received in said lower pockets to engage the supporting and driving shoulders of said pockets; and a driving bushing in said opening having shouldered portions at least equal in number to and received in the upper pockets to engage the supporting shoulders of the upper pockets, the driving bushing being of sufficient length to extend 60 partly into the table bushing but being supported by the supporting shoulders of the upper pockets at a sufficient elevation above the table bushing to be maintained entirely out of contact with the table bushing.

12. In a rotary machine of the class described, 70 the combination of: a base; a table rotatably supported by said base, said table having a top

- portion, a skirt depending therefrom, and a table opening through said top portion and skirt, said table opening having circumferentially staggered and alternately arranged upper and lower pockets of substantially the same diameter at the upper end thereof and accessible from the top of said table, said pockets respectively providing upper and lower supporting shoulders and driving shoulders extending from the supporting shoulders to the top surface of said table; a table bushing in said opening having shouldered portions equal in number to and received in said lower pockets to engage the supporting and driving shoulders of said pockets; and a driving bushing in said opening having shouldered portions equal in number to and received in both of the upper and lower pockets to engage only the supporting shoulders of the upper pockets but engaging the driving shoulders of both the upper and lower pockets.
13. In a rotary machine of the class described, the combination of: a base; a table rotatably supported by said base, said table having a table opening which is provided with alternately arranged upper and lower pockets of substantially the same diameter and accessible through the top surface of the table, said pockets providing respectively upper and lower supporting shoulders and driving shoulders extending from the supporting shoulders to the top surface of said table, a table bushing in said opening having shouldered portions equal in number to and received in said lower pockets to engage the supporting and driving shoulders of said pockets, and a multi-part driving bushing in said opening having shouldered portions equal in number to and received in both the upper and lower pockets to engage only the supporting shoulders of the upper pockets but engaging the driving shoulders of both the upper and lower pockets; the driving bushing being supported by the supporting shoulders of the upper pockets so as to depend partly into the table bushing but being entirely out of lateral contact with said table bushing; the driving shoulders of all of said pockets operating to prevent lateral expansion of the driving bushing parts into engagement with the table bushing.
14. As a new article of manufacture, a table for use as an element of a rotary machine of the class described, said table having a top portion, a skirt depending therefrom, and a table opening through said top portion and skirt, said table opening having alternately arranged upper and lower pockets of substantially the same diameter at the upper end thereof and accessible from the top of said table, the pockets respectively providing upper and lower supporting shoulders and driving shoulders extending from the supporting shoulders to the top surface of said table; the arrangement of pockets being such that the inner pockets only provide a series of driving shoulders at one elevation while both the upper and lower pockets form a series of driving shoulders at a higher elevation.
15. In a rotary machine of the class described, the improvement which comprises a table having a top portion, a skirt depending therefrom, and a table opening through said top portion and skirt, said table opening having alternately arranged upper and lower pockets of substantially the same diameter at the upper end thereof and accessible through the top of said table, said upper and lower pockets providing two entirely independent series of supporting shoulders with the said shoulders of the respective series being arranged at different elevations; the lower pockets having driving shoulders extending from their series of supporting shoulders past the upper pockets to the top surface of the table; and the upper pockets having driving shoulders extending from their series of supporting shoulders to the top surface of the table.
16. As a new article of manufacture, a table for use as an element of a rotary machine of the class described, said table having a top portion, a skirt depending therefrom, and a table opening through said top portion and skirt, said table opening having alternately arranged upper and lower pockets of substantially the same diameter at the upper end thereof and accessible from the top of said table, the pockets respectively providing upper and lower supporting shoulders and driving shoulders extending from the supporting shoulders to the top surface of said table; the arrangement of pockets being such that the inner pockets only provide a series of driving shoulders at one elevation while both the upper and lower pockets form a series of driving shoulders at a higher elevation, all of said pockets being of substantially triangular shape and of the same size in plan.

WILLIAM D. DAVIDSON.
